CLAIM

The ornamental design for a product hanger hole, as shown and described.

DESCRIPTION

FIG. 1 is a bottom perspective view of a product hanger hole, according to a first embodiment;

FIG. 2 is a top perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a bottom perspective view of a product hanger hole, according to a second embodiment;

FIG. 10 is a top perspective view thereof;

FIG. 11 is a front view thereof;

FIG. 12 is a rear view thereof;

FIG. 13 is a top view thereof;

FIG. 14 is a bottom view thereof;

FIG. 15 is a left side view thereof;

FIG. 16 is a right side view thereof;

FIG. 17 is a plan view of the product hanger hole of FIG. 9 in an open state showing the front and rear thereof; and, FIG. 18 is a plan view of the product hanger hole of FIG. 9 in an open state showing an interior thereof.

In the drawings, the dot-dash broken lines show portions of the product hanger hole that forms not part of the claimed design. The dash-dot broken lines are intended to show boundaries of the claim that form no part of the claimed design.

1 Claim, 14 Drawing Sheets
